BOTTLE WASHING APPARATUS

Filed May 25, 1922

F. J. B. Edward Brunhoff.

BY C. W. Miles.

ATTORNEY.

UNITED STATES PATENT OFFICE.

EDWARD BRUNHOFF, OF CINCINNATI, OHIO, ASSIGNOR TO THE BRUNHOFF MANUFACTURING COMPANY, OF CINCINNATI, OHIO, A CORPORATION OF OHIO.

BOTTLE-WASHING APPARATUS.

Application filed May 25, 1922. Serial No. 563,638.

My invention relates to improvements in bottle washing apparatus. One of its objects is to provide an improved combination or assembly for the purpose of conveniently and expeditiously washing bottles. Another object is to provide improved controlling means whereby the scouring and rinsing of the bottles is attained by the adjustment of a control lever from one to another of three different positions. Another object is to provide against the scouring material being lodged in the water supply conduits. Another object is to provide for the escape of flocculent sediments or precipitates, or similar substances having a tendency to float upon water. My invention also comprises certain details of form combination and arrangement, all of which will be fully set forth in the description of the accompanying drawings in which:

Fig. 1, is a front elevation of a bottle washing apparatus embodying my improvements and invention.

Fig. 2, is a central vertical section through the same.

Fig. 3, is a perspective view of the controlling valve detached.

Fig. 4, is a perspective view of the delivery end of the exit ports with an automatically actuated gate attached thereto.

Fig. 5 is a sectional detail taken on lines 5—5 of Fig. 2.

The accompanying drawings illustrate the preferred embodiment of my invention in which 15 represents the base or support adapted to be clamped to the floor of a sink or other position where the waste water may be freely drained away. Formed in the base is a substantially horizontal conical valve chamber 16 having a supply port 17 leading thereto. Water under pressure is supplied to the port 17 through a flexible rubber conduit 18 from the usual water service supply pipes. Leading from the upper portion of the valve chamber is a relatively smaller water exit port 19 which serves as an injector conduit to take up a percentage of an abrasive material 20, such as sharp quartz sand for instance, into a current of water of relatively high velocity flowing upwardly through the conduit 19 and a conduit 21 ex-

tending above the conduit 19 and to discharge the mixed water and abrasive material into the interior of a bottle thrust over the end of the conduit 21, where the abrasive material and water thoroughly scour and clean the interior of the bottle and the abrasive material waste water and scourings flow out at the neck of the bottle around the conduit 21 and into a cylindrical housing 22 terminating at its lower end in a perforated sheet metal cone 24 through which the waste water and scourings escape while the abrasive material is retained within the perforated cone to be used repeatedly.

Another exit conduit 26 leads from the side of the valve chamber 16 and further to the rear thereof than the exit port 19. The conduit 26 is curved so that its outer end lies alongside of the upper end of the conduit 21 and terminates within the bottle at about the same height as the upper end of the conduit 21. A sheet metal gate 27 is pivotally attached at 28 to the upper end of the conduits 21 and 26 and is automatically actuated by the jets of water so as to cover the upper end of the conduit 26 while water is issuing from conduit 21 to prevent water and abrasive material entering conduit 26, and actuated to automatically reverse and cover the exit end of conduit 21 when water is being delivered through conduit 26.

A hollow tapered valve plug 30 is seated in the valve chamber 16 and held in place by means of a cross-bar 44, see Fig. 1, which is rigidly attached to the base 15 across the open larger end of the valve chamber 16, and held a short distance from the casing 15 by means of screws 45 which pass through the ends of the cross-bar 44 and then through short sections of metal tubing and into threaded sockets in the base 15. A screw 46 is threaded through the cross-bar 44 along the axis of the valve plug 30, and its inner conical end engages a small tapered recess at the axis of the outer end of the valve plug, see Fig. 3, whereby the valve plug 30 may be adjusted with great accuracy to its tapered seat, and so as to insure the valve plug moving freely at all times. A lock nut on the screw 46 provides for locking the

screw 46 rigidly to its adjusted positions relative to the cross-bar 44. The valve plug 30 is provided with a port 31 to register with the port 17, and a port 32 to register with the port 19 of the valve casing when the valve handle or lever 35 is thrown to the left hand full line position shown in Fig. 1, to thereby supply water under pressure through the conduit 19 into the flaring end of conduit 21 where a certain amount of abrasive is taken up by the water jet and the water and abrasive delivered as a jet from the delivery end of conduit 21 into the interior of a bottle. The valve 30 is also provided with a port 33 to register with port 17 and port 34 to register with port 26 when the valve handle 35 is in the right hand dotted line position shown in Fig. 1. Thus the valve handle 35 indicates exteriorly of the valve casing, by its position the position of the valve and its ports inside of the valve casing.

When the valve handle 35 is in the vertical dotted line position Fig. 1, all of the ports through the valve 30 and valve casing 16 are cut off thereby providing for a convenient and ready control with a single operative lever.

A series of spring fingers 37 are attached to the cylindrical casing 22 and bent inwardly toward the centrally located conduits 21 and 26. The fingers 37 serve to yieldingly hold the inverted bottles in a central position relative to the bottle washing apparatus during the washing operation. A series of ports 38 at the upper portion of the conical perforated member 24 serve to permit the escape of any flocculent material or similar material washed from the bottles and which tends to float upon the water or refuses to pass through the smaller perforations of member 24. Each port 38 is preferably provided with a sheet metal hood 39 which serves to prevent the abrasive material being discharged through the ports 38.

In operation, when the valve handle 35 is in a substantially vertical position, the ports 31 and 33 do not either of them register with the port 17, and no water flows. When the valve handle 35 is moved to the left hand or full line position of Fig. 1, the port 31 registers with port 17, and port 32 registers with port 19, causing water and scouring material to be forced upwardly through the tube 21 into the bottle, while the upper end of the tube 26 is closed by the gate 27. When the valve handle 35 is in the right hand or dotted line position Fig. 1, clear water flows through ports 17 and 33 and into the valve chamber, and through ports 34 and 26 into the bottle to rinse the bottle, while the gate 27 closes the upper end of the tube 21. The ports 32 and 34 are off-set lengthwise of the valve 30 so as not to register with the port 17, and so that port 32 can

only register with 19, and port 34 can only register with port 26. The casing 22 is detachably held in place upon the member 24 by means of bayonet joint latch members 48.

The apparatus herein shown and described is capable of considerable modification without departing from the spirit of my invention.

What I claim is:

1. A bottle washing apparatus comprising a valve casing provided with a base for mounting the same, a supply conduit communicating with said valve casing, a vertically disposed nozzle leading from said valve casing, a perforated container for abrasive material mounted upon said valve casing and surrounding said nozzle, a tube aligned with said nozzle but spaced therefrom, adapted to deliver an abrasive charged current of fluid into a bottle, an imperforate splash shield mounted upon said abrasive container and surrounding said tube, means carried by said shield for retaining the bottle in inverted position about said tube, a rinsing conduit leading from said valve casing and terminating in a portion extending adjacent to and parallel with said tube for entry therewith within the bottle, and a multiway valve plug within the valve casing for selectively controlling the flow of water to said tube or said rinsing conduit.

2. A bottle washing apparatus comprising a perforated casing provided with resilient fingers to support a bottle in an inverted position, a base supporting said perforated casing and provided with a tapered valve casing open at its larger end and provided with a port to supply water under pressure thereto and two exit ports to independently supply jets of water under pressure to the interior of bottles supported by said fingers, a tapered and chambered valve plug seated in said valve casing and provided with ports to direct the supply of water to either of said exit ports, a valve lever to actuate said valve plug from the exterior of the valve casing and to indicate by its position the position of said valve plug within its casing, a bracket detachably attached to the valve casing, a set-screw carried by said bracket and adjustable to engage the larger end of said valve plug and to hold the valve plug in position relative to its valve seat within said valve casing, and means engaging the valve lever to limit the rotary movement of the valve plug within the valve casing by engaging the valve actuating lever at opposite limits of the movement of said lever.

3. A bottle washing apparatus comprising means to support a bottle in an inverted position, a conduit to supply a jet of mixed water and a scouring material to the interior of a bottle to be washed, a conduit to supply a jet of rinsing water to the interior of said bottle, a conduit to supply water under pres-

sure to said conduits, means controllable at will to alternately supply water under pressure through said scouring conduit or said rinsing conduit to the interior of the bottle, and a valve at the exit end of said scouring conduit and rinsing conduit and automatically actuated by the flow of water through

said conduits to alternately close the exit end of said scouring conduit and said rinsing conduit.

In testimony whereof I have affixed my signature.

EDWARD BRUNHOFF.
